UNITED STATES PATENT OFFICE.

JAMES DAVID KING, OF MERIDIAN, MISSISSIPPI, ASSIGNOR TO THE QUEEN CITY SAFETY APPLIANCE COMPANY, OF MERIDIAN, MISSISSIPPI.

SAFETY DEVICE FOR RAILWAY-CARS.

1,222,108.

Specification of Letters Patent. Patented Apr. 10, 1917.

Application filed January 27, 1916. Serial No. 74,645.

To all whom it may concern:

Be it known that I, JAMES D. KING, citizen of the United States, residing at Meridian, Mississippi, have invented certain new 5 and useful Improvements in Safety Devices for Railway-Cars, of which the following is a specification.

My invention is an improvement on the patent granted to Benjamin Hoover, April 10 6, 1915, No. 1,184,335, and is designed to simplify the construction shown and described in said patent.

In the accompanying drawing,

Figure 1 is a front elevation of my improved and simplified device;

Fig. 2 is a top view, and

Fig. 3 an end view.

The device belongs to that type in which the derailment of the train will open the 20 air line and apply the brakes so as to bring the train quickly to a standstill. I utilize in carrying out my invention a brake controlling train pipe having an opening closed by a valve normally with an oscillating arm 25 holding the valve and adapted to be moved on any derailment or other unusual condition to release the valve and by reducing the pressure in the air line to apply the brakes in the usual manner. Instead of the more 30 complex structure of the Hoover patent I use a vertically arranged spindle having an upper hooked end engaging the controlling valve, the lower end of the spindle carrying a lever through which the spindle is moved 35 by some suitable connection which in turn will be operated by any unusual position assumed by the train, as by derailment or the movement of the body of the car in relation to the trucks or the trucks in relation 40 to the rails, such a connection being shown in the Hoover patent and capable of assuming many forms, the only requirement being that there shall be a certain amount of lost motion to prevent the valve being opened 45 in the ordinary oscillations of the parts of the train when going over uneven rails or around curves, it being understood that only an abnormal displacement of the parts shall operate to oscillate the spindle and release 50 the valve.

In the accompanying drawings, A is the air pipe and B the valve, the valve as shown

in Fig. 3 being pivoted at a, to ears b and closing an opening c from the train pipe, suitable rubber gaskets d forming an air-tight connection between the valve and the opening in the pipe. A vertically arranged spindle e is supported in a bracket f projecting from the pipe line and this has a hooked end g which is formed with a knife 60 edge as at h, Fig. 1, engaging a groove in the upper face of a projection i, extending from the valve on the side opposite the pivot point of said valve. The projection i has its upper face rounded on the edges so that 65 as soon as the knife edge leaves the groove it will slide readily out of engagement with the valve and allow it to open quickly. The spindle has a slotted arm k fastened to its lower end and by the turning of this arm 70 the spindle is disengaged from the valve which is allowed to open under the pressure 75 of the air within the pipe.

Any suitable operating means may be held by the arm k, through its slot and be placed 80 in connection with any part of the train so as to be actuated by any abnormal movement of the parts to turn the arm k, and through it the spindle e, and thus allow the valve to open. It will be observed that this 85 makes a very simple construction, the pipe sections being made in one piece with the support for the valve and the support for the spindle; the valve constitutes but a single piece, the spindle a single piece and the arm 90 is connected thereto by a squared opening with a nut locked to the lower end of the spindle.

What I claim is:

1. In a safety attachment for railway 90 cars, a brake controlling train pipe, a pivoted valve closing an opening in the same, a member having one end directly engaging said valve to hold it closed, and means connected to the opposite end for oscillating 95 said member to positively disengage it from the valve to allow the valve to open, substantially as described.

2. In a safety attachment for railway 100 cars, a brake controlling train pipe, a valve closing an opening therein, a vertically arranged spindle having a hooked end directly engaging and holding the valve closed and means for oscillating the spindle to allow

the valve to open, substantially as described.

3. In a safety device for railway cars, a pipe section having formed thereon ears, a valve pivoted between said ears and closing an opening in the pipe section, a bracket also carried by the pipe section and an oscillating spindle carried thereby having a hooked end engaging the valve, and an arm

connected to said spindle for oscillating it, substantially as described.

In testimony whereof, I affix my signature in presence of two witnesses.

JAMES DAVID KING.
